UNITED STATES PATENT OFFICE.

JENNIE M. BODENSIEK, OF NEW YORK, N. Y., ASSIGNOR OF ONE-THIRD TO GOTTFRIED O. BODENSIEK, OF NEW YORK, N. Y., AND ONE-THIRD TO FRANK BROAKER, OF BROOKLYN, NEW YORK.

HIP-REDUCER.

1,126,367.

Specification of Letters Patent. Patented Jan. 26, 1915.

Application filed June 21, 1910. Serial No. 568,097.

To all whom it may concern:

Be it known that I, JENNIE M. BODENSIEK, a citizen of the United States of America, residing in New York, in the borough of Manhattan, county and State of New York, have invented certain new and useful Improvements in Hip-Reducers, of which the following is a specification.

This invention relates to an improved device for women's wear permitting the free motion of the body, and compressing or reducing the hip portion of the wearer; and the invention consists of a device comprising a body section, a leg section enveloping the legs, the body sections and leg sections being joined so as to form a unitary structure and all being yieldable to the movements of the body, and means at the front of the body and leg sections extending from the waist portion of the body section to the leg section downwardly at the front of the structure; and the invention consists further of a body section, leg sections, enveloping the legs, both sections being yieldable, and lacing straps with strings therefor at the front of the device, and extending from the waist portion to the leg sections downwardly below the crotch of the wearer; and the invention consists further of two body and leg sections made of elastic material and connected at their rear-ends and provided with lacing straps and strings at the front-part, the leg-sections being open below the lower end of the rear-seam but connected at their inner lower ends, and darts of elastic material inserted into the lower rear-ends of the leg-sections, the elastic ribs of the darts running in longitudinal direction and at an angle to the elastic ribs of the leg-sections.

In the accompanying drawing, Figure 1 represents a perspective front-view, Fig. 2 a perspective rear-view, and Fig. 3 a horizontal section on line 3, 3 Fig. 1, of my improved hip-reducer.

Similar letters of reference indicate corresponding parts throughout the figures.

Referring to the drawing, *a* represents the body-sections and *b* the leg-sections of my improved hip-reducer. The body and leg sections are made of suitable rubber elastic or other elastic fabric which expands in horizontal direction, the body-sections being connected by a seam *a*¹ at their rear-ends. The body-sections *a* are connected at their

front-ends with straps *a*² having eyelets and 55 a lacing string *d* which is passed through the eyelets and through inside loops *e* that are arranged at the upper edge of the body-sections so as to permit the tight fitting of the upper edge of the body-sections to the 60 waist and the tight closing of the same in front by the lacing string, which is tied together at the lower end of the straps *a*², as shown in Fig. 1. The straps *a*² extend downwardly about two-thirds the length of the 65 garment as shown in Fig. 1, from the waist portion to the leg-sections downwardly below the crotch of the wearer. The movement of the wearer brings about the co-operation of the strap with the leg-sections in such a 70 manner as to result in a downward and inward pressure on the hip-portion of the body and thereby exert a compressing action thereon.

The lower ends of the leg-sections *b* are 75 connected at their lower ends for a short distance at *b*¹, as shown at the lower parts of Figs. 1 and 2. The lower ends of the leg-sections are provided with garters or elastic loops for attaching the supports for the 80 stockings. At the lower rear-portion of each leg-section *b* is inserted a dart-shaped elastic *b*², the elastic ribs of which run not in transverse direction, but in longitudinal direction at an angle to the ribs of the leg-sections, so 85 as to permit the "giving" of the hip-reducer at the lower ends of the leg-sections when sitting down or stooping, and prevent thereby any strain on the thighs by the lower ends of the leg-sections. 90

The hip-reducer fits tightly yet comfortably around the hips and thighs owing to the yieldable material, preferably rubber, elastic or other elastic fabric and can be adjusted to the hips and abdomen by the front lacing 95 string. The hip-reducer is applied to the body in the same manner as the so-called knee-drawers, by passing the legs through the leg-sections, and then lacing down the front-section of the same. A very snug yet 100 comfortable fit is thereby imparted to the hip-reducing device, which is capable of "giving" in all directions in following the motion of the abdomen and thighs, without impeding the free motion of the same and 105 forming at the same time a reducing device for the hips and abdomen.

Having thus described my invention I

claim as new and desire to secure by Letters Patent:

A hip-reducer comprising two body and leg sections made of elastic material and connected at their rear-ends and provided with lacing straps and strings at the front-part, the leg-sections being open below the lower end of the rear-seam but connected at their inner lower ends, and darts of elastic material inserted into the lower rear-ends of

the leg-sections, the elastic ribs of the darts running in longitudinal direction and at an angle to the elastic ribs of the leg-sections.

In testimony, that I claim the foregoing as my invention, I have signed my name in 15 presence of two subscribing witnesses.

JENNIE M. BODENSIEK.
